SELECTING AND CALLING DEVICE FOR
AUTOMATIC TELEPHONE APPARATUS

Carl Josef Hilgers, Wuppertal-Barmen, Germany

Application March 24, 1933, Serial No. 662,594
In Germany January 28, 1932

18 Claims. (Cl. 179—90)

The known automatic telephone exchange apparatus have the drawback that if a mistake is made in dialling the particulars of the called private subscriber's station, the mistake is discovered only after the connection with the wrongly called subscriber has been established and the wrong subscriber has answered the call. Therefore a quite unnecessary loss of time and trouble result from a wrong dialling, both to the calling and to the wrongly called subscriber, and in addition the calling subscriber has to bear quite unnecessary expense in view of the fact that wrong connections made by an automatic telephone subscriber must be counted and paid for in exactly the same manner as correct connections.

It has already been proposed to provide in connection with automatic telephone exchanges, devices which show all the selected particulars of a call as a whole. By these known devices, the particulars of the call, for instance, the figures of the number of the selected station, are set by the manipulation of the dial, that is, by the dialling operation. Therefore the setting of the indicating device takes place simultaneously with the sending out of the current impulses so that when the mistake made during the dialling is shown by the indicating device, the connection with another subscriber has already been at least partly, but in some cases even completely, established. Consequently runners or other selecting means are quite unnecessarily brought into operation and the control lines or other connection channels used by the runners set in motion remain blocked to other subscribers, or if the mistake is made during the last dialling manipulation, an undesired call is effected. The known indicating device therefore does not fulfill its object. Moreover, it has the disadvantage that it necessitates making substantial modifications in the ordinary automatic telephone apparatus, so that in order to employ these indicating devices, entirely new automatic telephone apparatus have to be installed or existing apparatus have to be changed.

It has also been proposed to use an automatic calling device which can be released electro-magnetically from any suitable point and on being released automatically lifts the receiver and manipulates several times the dial forwards and backwards, and thereby establishes a certain predetermined connection and finally gives an alarm signal. The drive of the dial is in this construction effected by a power store which turns a disc provided with several toothed segments, the lengths of which corresponds to the figures of

the number to be called, said segments co-operating with a toothed gear fixed to the dial. Between the toothed segments gaps are provided which enable the dial to return to its initial position after each manipulation by a toothed segment. This known apparatus can be used only for establishing one particular connection for instance, a number determined by the lengths of the toothed segment, the connection being used, for instance, for raising an alarm.

The present invention provides a selecting and calling device for automatic telephone apparatus which enables the caller to select and set any desired number and/or other particulars of called station without sending out current impulses or in any way actuating any parts of the ordinary automatic apparatus. After the set call number and/or other particulars of the called subscriber's station have been examined and found correct, an operating device is released for instance by pressing a releasing button or other element, and this operating device automatically operates the selecting and calling device of the automatic apparatus in accordance with the previously set call number or particulars, whereby the required connection is automatically made. For this purpose a plurality of selectors serving for setting the particulars of a call is associated with an equal number of power stores serving for manipulating the dial of the automatic exchange apparatus in such a manner that on setting the particulars of a call, for instance the number of the called station, by means of the selectors, for instance figure carriers, the power stores are wound up by amounts corresponding to the set particulars, say figures. The power stores are adapted to be coupled individually one after the other with a driving element operating the dial so that on being released they drive the dial. After each manipulation by an individual power store the dial is released and then returned in the usual manner to its initial position. With the novel apparatus forming the subject of the invention, wrong connections are impossible, as the set particulars, say call number, can be examined before releasing the device operating the dial. If a mistake has been made in setting the particulars of the called station, the manually operated setting device can be returned to its initial condition by the operation of a second press button or like element, and consequently wrongly set particulars can be cancelled and a new selection can be made before the automatic apparatus is actually used. The invention therefore obviates the making of wrong calls and saves the

time and the noise connected therewith. Moreover, unnecessary sending out of current impulses and useless operation of runners or selecting members and wasteful blocking of control lines 5 is dispensed with. As the automatic apparatus is entirely unaffected during the setting of the required particulars of the station to be called, calls from other subscribers may be received by the would-be caller until the operating device 10 proper has been released by him. Moreover, the manipulation of the new device is extremely easy and simple, as the setting of the particulars, for instance number of the required station, is effected in a similar manner as by the manipulation 15 of the known dial. For setting the carriers of the figures or other particulars and for winding up the power store, a chain may, for instance, be used which is provided with finger rests or like elements suitably arranged in relation to a scale 20 of figures and/or a row of letters. In setting, for instance, a required call number, the finger is first placed above or to correspond with the first figure of the required number and the chain is moved by the corresponding finger rest or other 25 element appertaining to the selected figure down to a fixed stop, whereupon the finger is removed from the chain. A second figure or number is then set in the same manner and so on, until all the particulars have been selected. The selected 30 particulars, say figures, then appear in a window arranged near the selector mechanism and can be examined. After the accuracy of the required particulars of call has been checked, the device for automatically effecting the dialling and calling 35 is released by pressing down the button.

An important advantage of the invention is the fact that no changes of any kind need be made in the existing automatic apparatus, inasmuch as the device forming the subject of the invention 40 can be applied without any modification to any existing automatic telephone apparatus. For this purpose the device according to the invention may be housed in a separate casing which is mounted above the usual dial of the automatic 45 telephone apparatus, and may be directly clamped to the casing of the apparatus. Preferably the casing of the additional device is hinged to the casing of the telephone apparatus so that in case of need the additional device may be turned upwards to uncover the dial of the automatic apparatus and enable same to be manually operated in the usual way.

The accompanying drawings show by way of example one construction embodying the features 55 of the invention.

Fig. 1 is a top view of the new device.

Fig. 2 is an elevation showing the new device turned upwards the portion by which the new apparatus is fixed to the existing automatic apparatus being partly shown in section.

Fig. 3 is a top view of the new device with the top of the casing removed.

Fig. 4 is a section on line IV—IV of Fig. 3 seen from the right.

Fig. 5 is a section on line V—V of Fig. 3 seen from the front.

Fig. 6 is a section on line VI—VI of Fig. 3 seen from the right.

Fig. 7 is a section on line VII—VII of Fig. 3 seen from the rear.

Fig. 8 is a section on line VIII—VIII of Fig. 3 seen from the left.

Fig. 9 shows a portion of the means for operating the driving pinion and the reversing gear.

Figs. 10 and 11 show the "cancelling" press

button and the parts associated therewith in two views arranged at right angles to each other.

Fig. 12 is a diagrammatic view in which various gear parts actually lying in different planes are represented as lying in the same plane. 5

Fig. 13 shows a detail shown in the direction of arrow F of Fig. 12, and

Fig. 14 shows another detail shown in the direction of arrow G of Fig. 12.

The whole device is contained in a casing 1 (Figs. 1 and 2) which is normally located just above the dial 2 of an ordinary automatic telephone apparatus and is pivotally mounted in such a manner that it can be swung or turned upwards so as to uncover the dial and enable the 10 disc to be manually operated in the usual manner in case of need. For this purpose the casing 1 is, in the construction shown, hinged at 3 to a support 4 which can be fixed to the automatic telephone apparatus, namely to the socket portion 20 5 thereof carrying the dial 2, without the necessity of making any alterations in the existing apparatus. The support 4 of the casing 1 is in the construction shown made in the form of a ring (Fig. 2) the upper and wider portion of 25 which is rectangular in shape to correspond with the rectangular shape of the casing 1 and encloses with sufficient play the dial 2. The lower and narrower portion of the support 4 is cylindrical and is slid upon the upper end of the 30 socket 5 of the automatic apparatus carrying the dial. The lower portion of the support is slit and formed near the slits with eyes 6, so that it can be clamped to the socket 5 by means of screw bolts passed through the eyes. A strip of felt or 35 other soft or resilient material may be inserted between the socket 5 and the clamped portion of the support 4. In cases in which the socket 5 of an existing automatic telephone apparatus is placed so low that the carrier 4 cannot be clamped 40 thereto, the carrier is provided with a horizontal annular base portion 7 having a central aperture corresponding to the outer diameter of the usual neck portion 8 of the socket 5. The portion surrounding the central opening is formed with a slit 45 collar 9 provided with means for clamping same to the neck 8 of the socket. The clamping means may again, as in the previously described construction comprise two pairs of eyes and clamping bolts passed therethrough. In the second 50 construction of the support 4, the lower tubular portion is either shortened or entirely omitted.

As in the second construction of the carrier 4, the base portion 7 covers the figures or other particulars borne by the top of the socket 5 which 55 are of course required for the dialling operation, these figures and/or other particulars must be provided upon the top surface of the base portion 7 in the required position so as to correspond with the holes of the dial.

Upon the upper portion of the support 4 is provided a hinge 3 for the pivotal mounting of the casing 1. At the opposite side there may be provided any suitable locking device, for instance a bolt or a catch. The locking device is preferably 65 adapted to be releasable by means of a knob or other manually operated member so that in case of a breakdown of the device mounted in the casing 1, the whole device together with the casing can be easily swung into the inoperative position in which the dial 2 is uncovered and can be manually operated in the usual way. In some cases it might be advisable to provide the device forming the subject of this invention with an ordinary lock and key, or the previously men- 70 75

- tioned bolt or catch may be secured by means of a seal so that the casing 1 together with the device contained therein can be swung into the operative position only by an authorized person.
- 5 In that case it is advisable to lock or secure also the means for fixing the carrier 4 to the apparatus. For this purpose, the casing 1 may, for instance, be provided with a downwardly extending collar or flange or several lugs which in the 10 operative position of the casing enclose the clamping means of the support 4 and therefore render them inaccessible. In the construction in which the support 4 is fixed to the neck portion 8 of the socket 5 there is no need to provide any seal 15 for the clamping means, as in this construction, the clamping means are covered by the casing 1.
- With the exception of some apertures provided in the top of the casing (Fig. 1), the casing is entirely closed in order to prevent unauthorized 20 manipulation or access to the device contained therein. The top of the casing is provided with an elongated rectangular window 10 (Fig. 1) under which the figures of the selected call number appear. On the right of the window 10 there 25 is provided an elongated recess 11 the major axis of which is arranged vertically and the base portion of which is formed with a longitudinal slot 12. Under this slot is mounted the upper or front portion of a driving chain 16 which 30 passes over three chain wheels 13, 14, 15 and carries ten finger rests or carrier arms 17 which project upwardly through the slot 12 and are located within the recess 11. Under these finger rests or carrier arms 17 there is provided upon the 35 bottom of the recess 11 a scale 180 comprising figures 1 to 9 and zero, these figures being so arranged that in the idle position of the driving chain 16 there appears above each finger rest 17 its corresponding figure. The lower and if needed also the upper small side of the recess 11 are removed to enable the finger rests 17 to pass during the movement of the driving chain 16 from recess in the top of the casing into the casing itself. The driving chain 16 with its finger rests 40 and the corresponding figure marks serves for setting the required call number of the station to be called. It is, in this construction assumed that the stations are identified by numbers only. As the area of the casing 1 must be rather small, 45 that is not substantially larger than the socket 5 of a normal automatic telephone apparatus, and the dial 2, the portion of the driving chain 16 carrying the finger rests 17 and the scale 180 must be rather short. To enable the finger rests 50 17 to be placed at such a distance apart as would render manipulation of the chain with a finger easy and at the same time in order to make the figures of the scale 180 as large as possible, the finger rests 17 and the scale 180 are arranged on 55 both sides of the slot 12 and the chain 16, and the odd numbers and corresponding finger rests are arranged on one side, that is on the left of the slot, whilst the even numbers and the number 0 are arranged on the right side of the slot, the 60 figures and finger rests of the two rows being staggered relatively to each other as shown. The setting of a call number is effected by placing a finger upon the required figure of the scale 180 and then moving the finger together with the finger rest downwards to a stop formed at the 65 lower end of the recess 11. The finger is then removed from the finger rest, and the driving chain 16 is returned automatically by a spring (not shown) to its initial position, so that the opera-

tion of setting the next figure may be repeated in the same manner.

Above the window 10 there are provided in the top of the casing two apertures in which work press buttons 18, 19 of corresponding spindles or rods arranged within the casing. One of these press buttons, namely the button 18 serves for releasing, after the required call number has been set and found correct, the calling device proper arranged within the casing. The other button 19 serves for cancelling an incorrect setting by putting into operation a device which restores the parts which have been moved during the setting operation, to their initial positions.

The two press buttons 18 and 19 are provided with suitable indications, for instance "Call" and "Cancel". If preferred these indications may be arranged in the proximity of the buttons upon the top of the casing 1.

It is assumed in the constructional example illustrated that any subscriber's station is identified by a five-figured number. In accordance with this assumption there are provided under the window 10 the front portions of five endless bands 21, 22, 23, 24, 25 which are guided in the casing 1 partly by rollers 20 and partly by a fixed guide plate 26 (Fig. 4). The bands carry upon their front portion each the figures 1 to 9 and zero. The bands 21-25 are associated each with a corresponding spring motor 31, 32, 33, 34, 35 which serve for driving the dial 2. The five spring motors 31-35 which are all mounted upon a fixed shaft 28 within the casing 1, each has a cylindrical outer casing or drum adapted to rotate about the shaft 28. In each casing there is a suitable spring preferably made of several steel strips and constructed after the manner of a watch spring, a helical spring or a spiral spring, which is fixed at one end to the motor casing and is fixed at the other end to the stationary shaft 28. Around each spring casing is passed a flexible tension member for instance a metal band 29 forming a loop. The ends of this tension member are crossed and fixed to the corresponding figure band 21, 22, 23, 24 or 25 whereby these bands are positively coupled in both directions with their corresponding spring casings so that upon rotation of a spring casing a displacement of the corresponding band of figures will take place by an amount exactly corresponding to the amount of rotation of the casing. The rotation of each spring casing in the sense of de-tensioning or slackening the spring, is limited by steps, the arrangement of which will be hereinafter more fully described, in such manner that in the idle position of the spring motors and the figure bands coupled thereto, there appears under the window 19 a blank field corresponding to the initial position of the band and adjacent to the figure 1.

The casing of each of the spring motors 31-35 is provided upon its periphery adjacent to the portion bearing the before-mentioned tension member with a toothed rim 41, 42, 43, 44 or 45, all adapted to engage a pinion 30 which serves for winding up the motors 31-35 by rotating their spring casings. The winding up of the motors occurs simultaneously with the setting of the figures of the call number within the window 10, and varies as regards its degree with the magnitude of the set figure. The winding up of each motor continues until the figure corresponding to the selected finger rest of the scale 180 appears in the window 19. The common driving pinion 30 is driven by means of the above described driving chain 16. One pinion serves for

all the five spring motors 31-35 and is adapted to be brought into engagement with the toothed rims 41-45 of the motors. For this purpose the pinion 30 is slideable upon a prismatic shaft 140 which is operatively connected by gears 142, 143 with a shaft 144, the latter carrying the rear wheel 14 of the driving chain 16. Between the chain wheel 14 and the shaft 144 is interposed a yielding one-way coupling 36 (Fig. 12) so that the shaft 144 and the pinion 30 are rotated only during the downward movement of the front portion of the chain 16 carrying the finger rests 11, whilst during the upward movement of the chain, that is during the return of the finger rests 17 10 into the initial position, the shaft 140 remains stationary. The slideable pinion 30 is held in a control fork 37 which is fixed to a nut 38. The nut is mounted upon a rotatable but axially immovable screw spindle 39 parallel to the shaft 140, the pinion 30 being therefore operated by the rotation of the spindle. The spindle 39 is operatively connected by gears 46-51 with a shaft 40 on which is mounted a yielding one-way coupling 52, 53 (Figs. 6 and 12). The coupling member 53 rotatably mounted upon the shaft carries a radially extending carrier arm 141 and is controlled by a spring and a stop limiting its rotation in such a manner that in the idle position of the coupling the carrier arm 141 assumes the 15 position shown in Fig. 6. With the arm 141 is associated a pawl 54 carried by the driving chain 16, said pawl being in the idle position of the chain wheel 14 located in front of or anterior to the arm 141. During the manual drive of the 20 driving chain 16, the pawl passes the carrier arm idly, that is, without acting thereon. At the end of the return movement of the driving chain, the pawl carries the arm 141 and turns same through an angle of about 15°. This rotation of the arm 141 is transmitted by the one-way coupling 52, 53 to the shaft 40 and by the latter through the transmission 46-52 to the spindle 39. The arm 141 after having been passed by the pawl 54 returns under the action of a spring into 25 its initial position, the shaft 40 and the spindle 39 remaining during this movement stationary owing to the provision of the one-way coupling. The ratio of transmission of the gears 49-52 is so chosen with regard to the pitch of the spindle 30 that at each turning of the spindle 39 effected by the transmission, the nut 38 and the pinion 30 connected thereto by the fork 37, are moved by an amount corresponding to the distance between two adjacent toothed rims 41-45 of the 35 spring motor 31-35 so that the pinion is brought into engagement with the next following spring motor.

In the idle condition of the device, the pinion 30 is in the position shown in Figs. 3, 7 and 12 40 and is therefore operatively connected with the first spring motor 31. If now the driving chain 16 is moved by means of a finger inserted to select the first figure of the desired call number, the first spring motor 31 will be wound up by means 45 of the transmission 142, 143 and the pinion 30 and at the same time the first figure of the required number will be set to appear under the window 10. Upon the return of the driving chain 16 into its initial position, the spindle 39 will be 50 rotated by means of the coupling 52, 53 and the transmission 46-52, whereby the pinion 30 will be set to co-operate with the second spring motor. If now the chain 16 be moved a second time by means of a finger inserted to select the second 55 figure of the required number, the second motor 59

32 will be tensioned and in the window 10 the second figure of the number will appear. Upon a further return of the driving chain 16, the spindle 39 will again be rotated and the pinion 30 will be further moved, so that it engages the toothed rim 5 of the third motor 33. The above described operations are now repeated until all the figures of the required call number are placed in the window 10 and, in the case of a five-figured call number, all the five spring motors have been tensioned by amounts corresponding to the selected figures. Upon the return of the driving chain 10 which occurs after the selection and setting of the last number of the call number, the pinion 30 is moved into a position to the right of the last 15 spring motor 35 which is the extreme right position of the pinion. From this extreme right hand position the pinion is subsequently moved in a manner and by means hereinafter described, upon the starting of the drive of the dial 2 of the automatic apparatus. To enable this operation to be carried out, the transmission 46-51 is disengageable, for which purpose the two gears 47 and 48 20 of the transmission are mounted in a rocking lever 65 mounted upon a control shaft 66. 25

The spring motors 31-35 must, of course, be locked every time they have been wound up by the setting of the figures, until they are required to run under their own spring power to drive the dial. For this purpose the casings of the 30 motors are provided upon their right hand end faces with recesses or notches, and there is provided adjacent to each motor a spring controlled locking pawl 55 which automatically engages the notches or teeth of the corresponding spring motor casing. In the construction shown the locking pawls are arranged behind the spring motor casings, and are extended downwards in the front portion of the casing 1, carrying at their 35 ends arms 56 the operation of which will be here- 40 inafter described.

The spring motors 31-35 serve as previously stated, for driving the dial 2 of the automatic apparatus in accordance with the call number set in the window 10, whereby the required number 45 is called in known manner. For this purpose there is provided upon the other side of the spring motors, that is, opposite the pinion 30, another pinion 57 which is slideable upon a prismatic shaft 58 and is adapted to be set to co-operate with 50 the toothed rims 41-45 of the five spring motors one after the other.

The shaft 58 of the pinion 57 is operatively connected by a transmission 67, 68 with the shaft 69 carrying a toothed gear 70. The gear 70 engages the toothed rim 71 of a coupling disc 72 which is arranged coaxially with the dial 2 of the automatic apparatus, near the bottom of the casing 1 so that when the device 1 is in its working position, the disc 72 lies close above the dial. 60 The coupling disc 72 carries upon its underside a projection or finger 73 which engages the last hole of the dial 2. The coupling disc 72 is therefore adapted to carry the dial and turn same by any required amount. Between the gear 70 which 65 engages the coupling disc 72 and the shaft 69 carrying the gear 70 there is interposed a disengageable coupling 74 which after each turning operation of the dial 2 is automatically disengaged, to enable the dial and the coupling disc 72 70 connected therewith to return to their initial positions. The coupling 74 is normally held in the engaged position by a spring 75. The disengaging of the coupling takes place by means of a lever mechanism 76, 77 and a prismatic shaft 75

78 arranged parallel to the shaft 28 of the spring motors 31-35 (Figs. 4 and 12). The shaft 78 carries a disengaging arm 79 which moves together with the pinion 57, and is normally, when 5 the coupling is in the engaged position, held by the spring of the coupling in its position of rest. For co-operation with the disengaging arm 79, each spring motor 31-35 is provided with a rod 81 guides at right angles to the shaft 78, each of 10 the rods being provided with two recesses 82, 83 adapted to be engaged by finger 84 fixed upon the casing of the corresponding spring motor (Fig. 4). When the spring motors are in their idle positions, the rods 81 are in their forward end positions, in which the finger 84 engages the upper 15 recess 82. Upon a motor being wound up, the finger 84 of this motor moves the corresponding rod 81 backwards and then moves out of the recess 82. If the motor is wound up by more than 20 one complete revolution, the finger 84 enters at the end of the first complete revolution the second recess 83 and moves the rod 81 a further distance.

Upon the pinion 57 being set to co-operate with a spring motor, the disengaging lever 79 25 slide on prismatic shaft 78 is simultaneously brought into register with the rod 81 appertaining to this motor. The rod 81 has been moved from its idle position by the corresponding spring motor, whilst the motor was being 30 wound up, and consequently the disengaging lever 79 will now be located in front of the front end of the rod. If now the spring motor is caused to drive the dial, this operation being herein-after referred to as the "driving" operation of 35 the spring motor, the rod 81 will be moved back into its initial position, this movement taking place either in one or in two steps, depending on the amount to which the motor has been previously wound up. On returning to its initial 40 position the rod 81 strikes the disengaging lever 79 and thereby turns the shaft 18 in the sense of disengaging the coupling 74. The gear 70 is thereby disengaged from the shaft 69 so that the dial 2 after being driven by the motor, can 45 return together with the coupling disc 72 into the initial position. The pinion 57 is now set to co-operate with the next spring motor and at the same time the disengaging lever 79 moves away from the rod 81 by which it was previously 50 actuated and is brought into register with the rod 81 corresponding to the next motor. The disengaging lever 79 is at the same time released from its disengaging position, and the coupling 74 is again thrown in by its spring 55 55 for the next drive of the dial 2, the disengaging lever assuming its initial angular position. The return movement of the dial 2 and the coupling disc 72 connected therewith is effected by a spring force. For this purpose there is provided 60 in addition to the already existing return spring within the socket 5 of the ordinary automatic apparatus, an additional spring 80 which may, for instance, be fixed to the gear 70. This additional spring is, of course, tensioned during the 65 drive of the dial 2 and is unwound during the return movement of the dial.

The push rods 81 and the fingers 84 upon the casing of the spring motors 31-35 serve at the same time as a means for limiting the drive of 70 the spring motors, inasmuch as a motor casing will be stopped as soon as the finger 84 has entered the recess 82 of the rod 81 and has moved the latter to its end position.

The pinion 57 which transmits the drive from 75 the spring motor 31-35 to the coupling disc 72,

assumes in the idle position of the device the extreme position shown in Figs. 3, 5 and 12 in which, seen from above, it is located at the left of the first spring motor 31 and is therefore disengaged from all the motors. The displacement of the pinion 57 is effected by means of an operating fork which during its movement also carries the disengaging lever 79. The fork 85 is operated by means of a nut 86 slidably mounted upon a screw threaded spindle 101 parallel to 10 the prismatic shaft 58. The spindle 101 is moved partly by hand, namely for setting the pinion into engagement with the first spring motor 31, and is then further rotated automatically for setting the pinion step by step into engagement with 15 the remaining spring motors 32-35. The manual rotation of the spindle is effected by means of the call push button 18. This push button serves also for returning the pinion 30 which has been used for winding up the spring motors 20 31-35, and which after the setting of the required station number, is set with regard to the last spring motor. This pinion 30 must in order not to hinder the driving rotation of the motors, be moved into a position at the left of the first 25 spring motor 31, that is, into a position which corresponds with the position of the pinion 57 shown in Figs. 3 and 12. The following means is provided for the required manual operation of the screw threaded spindles 39 and 101. 30

The spindles 39 and 101 carry at their left ends the pinions 87 and 88 (Figs. 8 and 12) which may be operatively connected together by means of two intermediate gears 89 and 90, in such a manner that when connected they will rotate in 35 opposite directions. One of the intermediate gears, namely 89, is rotatably mounted upon a stationary shaft 91 and is in permanent engagement with the pinion 87 on the shaft 39. The gear 90 is mounted in the left arm of a double- 40 armed lever 92 loosely mounted upon shaft 91, and meshes with the gear 89. The lever 92 is normally held by a spring 96 in the position indicated by full lines in Fig. 8, in which position the two pinions 87, 88 are separately, that is, independently rotatable. The lever 92 can be moved by the pressure of a projection 97 provided at the lower end of the rod 95 of the push button 18 into the position indicated by dotted lines in Fig. 8, in which position the intermediate gear 45 90 meshes with the pinion 88 of the spindle 101 so that the two spindles 39 and 101 are coupled to rotate simultaneously in opposite directions. This displacement of the lever 92 takes place during the last portion of the downward stroke 50 of the push button 18. At the side and above the intermediate gear 89 is mounted a gear 94 which is movable up and down and simultaneously rotatable within a slot guide 145, and is normally held in its upper end position by a 55 spring 93. In this position the gear 94 does not engage the intermediate gear 89. The gear 94 co-operates with a toothed rack provided upon the rod 95 of the push button 18 in such a manner that on depression of the button 18 the gear 60 94 is first pressed downwards by the rod 95 until it comes into engagement with the gear 89, whereupon the gear 94 is rotated by the toothed rack of the rod 95. This rotation is then transmitted according to the position of the lever 92 65 70 either by the gear 89 to the spindle 39 alone, or to both the spindles 101 and 39. The projection 97 provided upon the rod 95 of the call push button 18 has the further function of operating at the beginning of the downward stroke of the 75

push button 18 a lever 99 and turn same to one side. The lever 99 is mounted upon the control shaft 66 of the disengaging lever 65 of the gears 47, 48 of the transmission 46-51 driving the feed spindle 39 of the pinion 30. The lever is normally held in the position in which the transmission is thrown in. Upon the lever being swung to the side by the projection 97, the transmission 46-51 is thrown out of action. When, 5 after the setting of the number of the required station and the winding up of the spring motors 31-35 effected by the setting, the operator depresses the call button 18, the transmission 46-51 appertaining to the spindle 39 is first disengaged, and the gear 94 is engaged, whereupon 10 the toothed rack of the rod 95 rotates the gear 94 in the manner previously described. The spindle 39 of the nut 38 operating the pinion 30 is now rotated by means of gears 89, 87 in a direction opposite to that in which it was rotated 15 during the winding up of the spring motors 31-35 and the result is that the pinion 30 is moved into its extreme left position in which it is located at the left of the first power store or 20 spring motor 31. Before the pinion 30 reaches its extreme position, namely, at the moment at which it stands at the spring motor 31, the rocking lever 92 is turned by the projection 97 of the rod 95 in the direction of the arrow b (Fig. 25 8) so that gear 90 is also brought into engagement with pinion 88 of the spindle 101. During the further displacement of the pinion 30, the other pinion 57 will also be simultaneously displaced, and will be moved from the extreme 30 position shown in Fig. 12 so far to the right that it comes into engagement with the toothed rim 41 of the first spring motor 31. The displacement of the pinions 30 and 57 is completed upon the press button 18 reaching its lowest position. 35 The press button can now be released, whereupon the rocking lever 92 is returned by the spring 96 to its initial position, whereby gear 90 is put out of engagement with pinion 88 and the two spindles 39 and 101 become again independent. 40 45 At the same time the gear 94 moves upwards and comes out of engagement with the gear 89.

The further displacement of the pinion 57 is as above mentioned effected automatically. For this purpose the spindle 101 is connected at its 50 right end by a transmission 59-64 with a spring motor 100 (Fig. 12), said motor being in a similar manner as the spring motors 31-35 constituted by a casing rotatably mounted about a fixed shaft and a spring mounted within the casing and fixed at one end to the casing and at the other end to the stationary shaft. The spring may again be a torsional or watch spring consisting preferably of two steel bands. Between the last gear 64 of the transmission of the spring 55 motor 100 is inserted a one-way coupling 101 which is so arranged that the spring motor carries the transmission only when moving under its own power, that is by the unwinding of the spring, whilst when the motor is being wound up, the transmission remains stationary. The spring motor 100 is wound up at the same time as the spring motors 31-35 during the setting of the required station number. For this purpose the casing of the motor is connected by a 60 second one-way coupling 102 with the chain wheel 15 of the chain 16 carrying the finger rests 17 in such a manner that the motor casing is moved in the sense of winding up the motor 100 during the manual operation of the driving chain 70 75 16. In order to lock the spring motor 100 in its

wound up condition, there is provided upon one of the gears of the transmission 59-64, for instance, upon the gear 60, (see Fig. 14) a pin 103. With this pin 103 co-operates one of a plurality of pins 104 which are radially arranged upon one half 105 of a one-way coupling 105, 106 rotatable about a fixed shaft 107, in such a manner that in the idle position of the coupling half 105 one of the pins 104 lies always in front of the striker pin 103 of the gear 60 and holds the gear 10 locked against the turning moment exerted by the spring motor 100 (Figs. 12 and 14). The second half 106 of the one way coupling carries a carrier arm 108 turned downwards by a spring, said arm co-operating with the coupling disc 72 15 of the dial 2. In the coupling disc 72 is provided an opening 109 into which the arm 108 enters so that it can subsequently be carried by the coupling disc. In the idle position of the coupling disc 72 the arm 108 engages the opening 20 109 and assumes the position shown in Fig. 14. If now the coupling disc 72 is rotated in the direction of driving the dial 2, the disc carries the arm 108 and the coupling half 106 idly until the arm moves out of the opening 109, whereupon 25 the arm slides upon the surface of the disc 72 (dotted position in Fig. 14).

If now the dial 2 and the coupling disc 72 return to their initial positions, the arm 108 again enters at the end of the return of the disc 30 72, the opening 109 and is turned back into its initial position. During this movement of the arm 108, the coupling half 106 carries the other coupling half 105 provided with the pins 104 and the result is that the latter half is shifted by 35 the angular distance of two adjacent pins 104. During this movement the gear 60 is first released for rotation whereupon the next pin of the coupling half 105 comes in front of the pin 103 of the gear 60, so that the latter gear is again 40 locked after a full revolution. The spindle 101 is therefore rotated by an amount corresponding to a complete revolution of the gear 60, and owing to a proper selection of the ratio of transmission from the gear 60 to the spindle 101, the 45 nut 86 together with the pinion 57 will be shifted by an amount corresponding to the distance between the toothed rims 41, 42 and so on of the spring motors 31-35, whereby the pinion 57 will be set for co-operation with the next following 50 spring motor 32 and so on. After this motor has performed its driving rotation, and has again driven the dial 2, the coupling member 105 will at the end of the return of the dial 2, be again rotated by the distance between two pins, so 55 that the above described operation will be repeated. It will thus be seen that the pinion 57 after having been first set to co-operate with the first motor 31, will thereafter be automatically set successively into co-operation with the 60 following spring motors 32-35.

The following means are provided for releasing the spring motors 31-35 for their driving operation each time when the pinion 57 is brought into engagement with the toothed rim 65 of a motor. For this purpose the fork 85 connecting the pinion 57 with the nut 86 is provided with an arm 110 which acts upon the release arms 56 of the locking pawl 55 of the spring motors 31-35 in such a manner that when the 70 pinion is brought into engagement with a motor, the locking pawl of this motor is brought out of action. Upon the pinion 57 being then moved further, the arm 110 clears the arm 56 of the locking pawl, whereupon the locking pawl re- 75

turns under spring action into its normal position. When after all the spring motors have performed their driving operations, the pinion 57 returns into its initial position, the arm 110 passes idly the arms 56 of the locking pawls. For this purpose the arm 110 is so mounted that on being displaced to the left it yields and passes the arm 56.

The return into the initial position of the pinion 57 which transmits the drive of the dial 2, is also effected by the spring motor 100. For this purpose the transmission 59-64 between motor 100 and spindle 101 is constructed as a reversing gear, the gears 62, 63 and 63a of the transmission being for this purpose mounted in a double-armed rocking lever 111. This rocking lever is normally in the position shown in Fig. 9 in which the gear 63 meshes with gear 64, whilst gear 63a is not in engagement with gear 64. Upon the rocking lever 111 being turned in the direction of arrow c (Fig. 9), gear 63 is moved out of engagement with gear 64, and at the same time gear 63a is brought into engagement with gear 64, whereby the direction 25 of rotation of the following gears and consequently also that of the spindle 101 is reversed. The rocking lever 111 is normally held by a spring 112 in the position shown in Fig. 9. Its movement in the direction of arrow c is effected, 30 for instance, by a wedge member 113 (Fig. 12) which is connected by a rod 114 with a rod 115 guided to move parallel with spindle 101. With the rod 115 co-operates one arm 116 of a double armed lever 116, 117 mounted upon the nut 86 of the pinion 57, the other arm 117 being adapted to co-operate with two stationary stops 118, 119. When pinion 57 after the last spring motor 35 has performed its driving operation, is moved to the right by the spindle 101, the arm 40 117 of the lever 116, 117 strikes the stop 118 situated at the right end of the travel of the pinion 57, and is turned by the stop anticlockwise. At the same time the arm 116 enters a recess 120 of the rod 115 and moves the rod to the right, 45 whereby the wedge member 113 is caused to move the rocking lever 111 in the direction of arrow c (Fig. 9) which reverses the transmission 59-64. The spring motor 100 now drives the spindle 101 in the opposite direction so that the pinion 57 50 is moved to the left. In order that the locking device of the gear 60 should not prevent during the return of the pinion the required opposite rotation of the gear, the striker pin 103 is pivotally mounted in such a manner that it forms a rigid stop only during the rotation of the gear 60 in the sense of displacing the pinion 57 to the right, whilst during the opposite rotation, that is, during the return of the pinion, it will turn and pass the striker pins 104 of the coupling 105. During the return movement of the pinion 57 to the left, the arm 116 of the lever 116, 117 leaves the recess 120 and then slides upon the rod 115. As soon as the pinion 57 reaches its extreme left position, the arm 117 60 strikes the left stationary stop 119 and is turned thereby clockwise. The arm 116 in co-operation with a nose 120 provided upon the rod 115, then moves the rod 115 to the left whereby the wedge piece 113 is caused to release the rocking lever 111. The rocking lever then returns to its idle position under the action of a spring, whereby the transmission 59-64 is again set for driving the spindle 101 in the sense of moving the pinion 57 to the right.

75 Upon the return of the pinion 57 into its initial

or idle position, the pinion 30 which serves for winding up the spring motors 31-35 must be got ready for action, that is, it must be set to co-operate with the first spring motor 31. This is effected by the transmission gears 89, 90 mounted 5 in rocking lever 92 (Fig. 8), the rocking lever being brought during the last portion of the return movement of the pinion 57 into the position shown in dotted lines in Fig. 8, in which position the gears 89, 90 operatively connect the pinion 88 10 mounted upon spindle 101 with pinion 37 mounted upon spindle 39. For this purpose the arm of the rocking lever 92 adjacent to the spindle 101 is provided with a lateral projection 121 having upon its under side a bevelled and also a horizontal surface, whilst the control fork 85 of the pinion 57 is provided with an arm 122 adapted to co-operate with said projection (Figs. 12 and 13). Some time before the control fork 85 and pinion 57 reach their extreme left positions, the bent 15 end 122a of the arm 122 strikes the projection 121 of the lever and in acting upon its bevelled surface turns the lever 92 into the position shown by dotted lines in Fig. 8, whereby the spindle 101 is coupled with spindle 39 through transmission 88, 90, 89, 87. The spindle 39 is now also driven, the drive being in the required direction to cause nut 38 together with pinion 30 to move to the right. As soon as nut 86 and pinion 87 have reached their extreme left positions, pinion 30: 20

30 has also been moved the required distance, that is, it has been set to co-operate with the first spring motor 31. The end 122a of the arm 122 now comes under the bent out portion 121a of the arm 121 of the locking lever 92 and thereby 35 releases the lever. The lever 92 is now swung back by the spring 96 into the position shown by full lines, and the two spindles 101 and 39 are disconnected. The device is then ready for the setting of a fresh station number. 40

In the foregoing description of the means for returning the pinion 57 into its initial position, and the simultaneous setting of the pinion 30 for co-operation with the first spring motor, it has been assumed that the number required for calling a station comprises five figures and that therefore the pinion 57 always moves into its extreme right position. In practice it may be necessary to provide for the use of station numbers having fewer than five figures, in which case the 50 pinion 57 will after the spring motors have performed their driving operations, not reach its extreme right position. In order to obtain even in these cases the automatic return of the pinion 57 into its initial position and in order to set at 55 the same time the pinion 30 to co-operate with the first spring motor 31, the ends of the push rods 81 appertaining to the spring motors 31-35 which co-operate with the releasing lever 79 of the coupling 74, are utilized also as stops for 60 controlling the control lever 116, 117 of the rod 115. For this purpose the push rods are arranged in one plane with the stop 118, 119 in such manner that the ends of the push rods 81 lie when the rods are in the idle positions in the path 65 of the arm 117 of the lever 116, 117 travelling with the pinion 57 (Fig. 4). Moreover, there are provided in the control rod 115 five recesses 120 arranged at even distances apart, which serve for engaging the lever arm 116. If, for instance, 70 a two-figured number has been set by the operator and consequently only the two spring motors 31 and 32 have been wound up, only the push rods 81 of these motors 31 and 32 were lifted and consequently rods 81 of the remaining spring motors 75

are in their initial positions of rest. When the lever arm 117, on pinion 57 being set for co-operation with the first and second spring motors, passes the push rod 81 of these motors, then upon completion of the driving rotation of the second spring motor 32, the arm 117 strikes upon the last displacement of nut 86 of pinion 57, the end of the push rod 81 of the third spring motor 33, whereby the lever 116, 117 is turned 5 anticlockwise. Arm 116 then engages the adjacent recess 120 of the control rod 115 and shifts the rod to the right, whereby the transmission gear 59-64 of the motor 100 is reversed and the return of the pinion 57 into its initial position is 10 started. If a one-figure or a three-figure or a four-figure number was set by the operator, then the lever 116, 117 is operated by the push rod 81 of the second motor 32, or the push rod 81 of the fourth spring motor 34 or of the fifth motor 35 15 as the case may be. It will thus be seen that the return of the pinion 57 into its initial position will in any case be started after the last of the previously wound up spring motors has performed its driving operation. Simultaneously with the 20 return of the pinion 57 into its initial position, the pinion 30 is brought into engagement with the first motor 31.

To insure that the lever 116, 117 should not be 25 acted upon by the push rods 81 during the return 30 of the pinion 57 into its initial position, the free end of the lever arm 117 which co-operates with these push rods is constructed as a pivoted pawl member in such a manner that the lever 117, 116 can be turned by the push rods 81 only during the 35 movement of the pinion 57 from the left to the right, whilst during the opposite movement of the pinion 57 from the right to the left, the free end of the lever arm 117 will yield on coming into contact with the ends of the push rods. The 40 stationary stop 119 provided at the left end of the travel of the pinion 57 is so placed in relation to the ends of the push rods 81 and the right hand stationary stop 118, that it does not co-operate with the pivoted yielding end of the lever 116, 45 117, but only with the rigid part of the lever arm 117. This construction of the lever 116, 117 is not particularly shown in the drawings.

To enable the spring motor 100 to effect the 50 movement of the pinion 57 to the right and also 55 return of the pinion into its initial position, means must be provided for fully winding up the motor 100 on setting the number of a called station, independently of the fact whether a high or low station number is set. For this purpose, the 60 ratio of transmission of the transmission 59-64 is so chosen that a few turns of the motor 100 are sufficient for providing the required number of revolutions of the spindle driven by the motor. The motor will in that case have to perform only 65 a few revolutions on being wound up, and it will therefore be fully wound up after only a part of the called station number has been actually set by the operator. During the remaining setting operation the motor will not be affected. For this 70 purpose, a yielding clutch, for instance a frictional clutch, may be interposed between the chain wheel and the motor 100, said clutch allowing slipping between its two halves as soon as the motor has been fully wound up. Instead of making the ratio of transmission between motor 100 and the spindle 101 very high for the purpose stated, a transmission device may be interposed 75 between the chain wheel 15 and the motor 100.

If during the setting of the called station's 75 number a mistake has been made by the operator,

that is to say, if a wrong figure has been set, a device may be brought into action by pressing the previously mentioned cancelling button 19, by which the spring motors 31-35 are caused to perform their rotations without driving the dial 5 2 and by which the set figures are simultaneously cancelled. This device is constructed as follows:—

The rod 123 of the cancelling button 19 is provided with a toothed rack which co-operates with 10 a gear 124 adapted to engage and drive a gear 150, the latter meshing with a pinion 127 fixedly mounted upon the left end of the threaded spindle 38 (Figs. 10, 11 and 12). The gear 124 is in a similar manner as the previously described gear 15 94 of the call button 18, slidably and rotatably mounted in a slot guide and is normally held by a spring 134 in an upper end position in which it does not engage the gear 150. Upon depression of the button 19, the gear 124 is first 20 moved downwards by the toothed rack 123 and is then turned by the toothed rack. The arrangement of the toothed rack 123 and the gears 124, 150, 127 is such that on depression of the toothed rack 123, the spindle 38 is rotated so as to move 25 the pinion 30 to the left. Upon the rod 123 of the cancelling button 19 there is also provided a projection 128 which co-operates with a lever 129 mounted upon shaft 66 which latter serves for disengaging the transmission 46-51. The rod 30 123 carries also a projection 162 which by means of a pivoted lever 130 acts upon a projection 131 of a release rod 132 which latter is guided parallel to a prismatic shaft 140 (Figs. 10, 11 and 12). The rod 132 carries a number of projections 133 35 co-operating with the locking levers 55 of the spring motors 31-35, said projections being so arranged that when the release rod 132 is moved to the right, all the locking levers 55 are simultaneously disengaged from the motors. A spring, 40 not shown in the drawings, tends to move the rod 132 back into its extreme left position. Upon the cancelling button 19 being depressed, the transmission 46-51 of the spindle 38 is first disengaged by means of projection 128, lever 129 and 45 shaft 66 so that the spindle 38 can rotate freely. The release rod 132 is moved to the right by the projection 162 and lever 130 and the wound up 50 spring motors 31-35 are released so that they can unwind idly. All the motors with the exception 55 of the one upon which the pinion 30 has been set, then unwind. During further depression of the button 19, spindle 38 is driven by means of toothed rack 123 and gears 124, 150 and 127, and this causes the nut 38 together with the pinion 30 to move to the left until the pinion has returned to its initial position (Fig. 12). As soon 60 as the pinion 30 becomes disengaged from the toothed rim of the motor upon which it was last set, this motor too unwinds its spring, so that all the spring motors 31-35 and the pinion 30 are again in the required initial position for setting 65 a fresh station number. The press button 19 is then released and returns under the action of its spring to its extreme upper position. At the same time, the projection 162 releases the release rod 132 and allows same to return to its initial 70 position. The projection 122 releases the lever 129 so that the transmission 46-51 is again engaged. The whole device is now ready for setting a fresh number.

The cancelling button 19 may be used by the operator not only after the complete setting of a station number, but even when the station num- 75

ber has been only partly set and an error has been made in the setting. If the cancelling operation is started after only a part of the spring motor 31-35 has been wound up, the press button 19 need not be depressed completely for returning the pinion 30 to its initial position, but it is sufficient to depress the button through a smaller distance corresponding to the number of the actually wound up spring motors. In order to prevent the pinion 30 from being moved by an excessive depression of the press button 19, beyond the required position, means are provided for automatically limiting the return movement of the pinion 30. This means may, for instance, consist of a projection 147 adapted to be lifted and depressed and mounted upon one arm of a double armed lever 148 (Figs. 10, 11 and 12). This projection 147 is normally inoperative and is upon depression of the cancelling button 19 moved into its operative position by a projection 139 of the rod 123 of the press button 19, the result being that the operating fork 37 of the pinion 30 strikes the projection 147 as soon as the pinion during its return movement has reached the position in front of the spring motor 31, whereby further movement of the pinion is stopped. Consequently, the press button 19 cannot be further depressed. If the press button 19 is now released and returns to its top position, the projection 147 is removed by a spring acting thereon from its operative position.

The operation of the device is as follows:—

In order to call a subscriber's station, the particulars of the subscriber's station, for instance a five-figured number, is first set by repeatedly manipulating the chain 16, which causes the figures of the called number to appear one after the other in the window 10 and also causes winding up by corresponding amounts of the spring motors 31-35. The spring motor 100 is also wound up at the same time. During this setting operation, it is not necessary that the receiver of the automatic apparatus be lifted from the hook. Only after the setting has been completed, must the receiver be lifted in order to release the normally locked dial 2. The press button 18 is then depressed whereby as previously described, the pinion 30 is moved into a position at the left of the first spring motor 31 and at the same time pinion 57 is brought into engagement with spring motor 31. Spring motor 31 now drives the dial 2 by an amount corresponding to the first figure of the number to be called. After return of the dial, pinion 57 is set by spindle 101 and motor 100 to co-operate with the second spring motor and so on until all the spring motors previously set have been unwound to drive the dial and the dial 2 has been five times driven by amounts corresponding to the figures to be called, performing return runs between operative runs. The connection with the required subscriber is then completed. After the last spring motor has performed its driving operation, the transmission of the motor 100 is reversed and the pinion 57 is returned to its initial position and pinion 30 is set to co-operate with the first spring motor 31, so that the whole device is ready for a fresh operation.

A similar operation takes place if the number of the called station comprises less than five figures, except that the dial instead of being driven five times is driven only once, twice, three or four times, as the case may be. Return of the pinion 57 into the initial position takes place in this case after the last of the previously wound

up spring motors has performed its driving operation.

Before operating the call press button 18, the operator must, of course, see whether the required number has been properly set. If a mistake has been made, the operator presses the cancelling button 19 whereby the previously wound up spring motors 31-35 are caused to run idly under their own spring power, and the pinion 30 is again brought into engagement with the first spring motor 31. The required number is then set again.

It will be understood that various changes and modifications are possible within the scope of the invention. It is, for instance, not necessary that the carrier 4 of the pivoted casing 1 should extend above the dial 2 and should enclose the dial. The carrier may, if preferred, have only a small height in which case the under side of the casing 1 may be provided with a downwardly extending collar which when the casing 1 is in the operative position, encloses the dial 2 and the coupling 72. This construction has the advantage that when the casing is tilted up as shown in Fig. 1, the dial 2 is quite free on all sides and is therefore more accessible for ordinary manipulation. The new device need not necessarily be fixed to the socket 5 carrying the dial 2 or to the member 8 of the socket. If, for instance, direct fixing of the device upon the socket 5 is not possible and if the socket does not possess a stationary but only a rotatable collar, the carrier 4 of the casing 1 may be fixed to the cover of the box containing the automatic apparatus by the aid of suitable fixing means, for instance, a collar or flange. When constructing and installing new automatic telephone apparatus, the device forming the subject of the invention may be fixedly mounted in the apparatus and form part thereof. Moreover, the new device may be mounted in a casing entirely separate from the ordinary automatic apparatus, and the casing may be placed near the automatic apparatus upon a table or may be fixed or mounted upon a wall. In that case, the drive of the dial 2 of the ordinary apparatus might be effected from the shaft 69 provided with a coupling 74, by the aid of a flexible shaft which carries upon its free end a pinion adapted to engage a toothed rim fixed to the dial 2, for instance, by clamping. The end of the flexible shaft carrying the driving pinion may then run in a small bearing fixed to the known stationary stop arm of the selector socket 5. The number of the bands 21, 22 and so on and the spring motors 31, 32 and so on, may, of course, be increased or reduced according to requirements. This depends upon the number of stations to be served and also on the particular system of identification of stations, which may necessitate the employment of additional particulars. Instead of endless bands 21, 22 etc. carrying the figures, ordinary, that is not endless bands might be used to display the selected figures under window 10 of the casing 1. In that case the bands should consist of flexible but comparatively stiff material, for instance, celluloid strips, so that they may be moved forwards and backwards by the aid of tension members 29.

I claim:

1. A device for facilitating correct dialling of automatic telephone apparatus comprising in combination: means for selecting at will and visibly indicating particulars of a proposed call; means for automatically driving the dial of an automatic telephone apparatus in accordance

with the selected set of particulars, controlled by said first mentioned means; and a casing enclosing the complete device and provided with means for fixing said casing to the neck portion 5 of the socket of an existing automatic telephone apparatus.

2. A device for facilitating correct dialling of automatic telephone apparatus, comprising in combination: means for selecting at will and 10 visibly indicating particulars of a proposed call; means for automatically driving the dial of an automatic telephone apparatus in accordance with the selected set of particulars, controlled by said first mentioned means; a casing enclosing 15 the complete device; a carrier for said casing adapted to be fixed to an existing telephone apparatus below the dial of such apparatus, said casing being hinged to said carrier to enable the whole device to be moved into and out of the 20 operative position.

3. A device for facilitating correct dialling of automatic telephone apparatus, comprising in combination: a plurality of means for visibly indicating particulars of a selected call; a plurality 25 of power storage means associated with said indicating means; a manually operable means for setting said indicating means and simultaneously winding up said power storage means by amounts corresponding to the movements im- 30 parted to said indicating means; means for successively coupling one after the other said power storage means with the dial for operating the latter; and means for uncoupling said power storage means from the dial after each manipu- 35 lation.

4. A device for facilitating correct dialling of automatic telephone apparatus, comprising in combination: a plurality of spring motors; a plurality 40 of means for visibly indicating particulars of a selected call associated with said spring motors; a manually operable device for operating said spring motors and associated indicating means; means for coupling said manually operable means successively with each of the 45 plurality of spring motors and associated indicating devices; means for automatically returning said manually operable means to its initial position after each operation; means for transmitting the return movement of each spring motor under 50 its own power to the dial of an automatic telephone apparatus; means for successively coupling each spring motor with the means for transmitting their movement to the dial; and means for causing all the spring motors and associated indicating means to return to their initial 55 position under the power of the spring motors, without driving the dial for the purpose of cancelling an incorrectly set number of particulars.

60 5. A device for facilitating correct dialling of automatic telephone apparatus, comprising in combination: a plurality of power storage means; means for visibly indicating particulars of a selected call associated with said power stor- 65 age means; a manually operable means comprising a driving chain provided with finger rests and associated with an indicating scale, for winding up said power storage means and setting simultaneously said means for indicating par- 70 ticulars of a selected call; means for automatically returning to its initial position said manually operable means after each operation; means for locking said power storage means after each setting operation; means for transmitting the re- 75 turn movement of said power storage means to

the dial; means for successively coupling said power storage means with said dial, to drive the dial a number of times in accordance with the selected set of particulars; means for starting the operation of the device upon the dial, by 5 releasing the first of said power storage means; and means for independently re-setting the indicating and the storage power means to their initial position without actuating the dial for the purpose of cancelling a wrongly selected call. 10

6. A device for facilitating correct dialling of automatic telephone apparatus, comprising in combination: a plurality of spring motors mounted upon a common shaft; a plurality of adjustable indicator means for indicating particulars 15 of a selected call, each spring motor being associated with a corresponding indicator means; a manually operable means for operating an indicator means for the purpose of displaying one particular of a call and simultaneously winding 20 up the associated spring motor by a corresponding amount; means for successively coupling said manually operable means with each of the spring motors; a driving member operatively connected with the dial of the automatic telephone appa- 25 ratus; means for successively coupling said driving member with each of the spring motors; and means for uncoupling said driving member from said spring motors after the operation of a dial; means for locking said spring motors in the 30 wound up condition; and means for unlocking said spring motors successively to enable them to drive successively one after the other the dial; and means for unlocking simultaneously all the 35 spring motors to enable them to return to their initial positions and return simultaneously the indicator means to their initial positions, prior to coupling said spring motors to the driving member operating the dial, for the purpose of cancelling an incorrectly set call; a second manu- 40 ally operable control member for controlling the operation of the means for coupling the spring motors with the driving member of the dial; and a third manually operable means for controlling the means for unlocking simultaneously the 45 spring motors for the purpose of cancelling a wrongly set call.

7. In a device of the kind described for facilitating the correct dialling of automatic telephone apparatus, the sub-combination of: a plurality of 50 spring motors mounted upon a common shaft; a plurality of indicators each associated with a corresponding spring motor; a manually operable means for operating said spring motors and associated indicators; means for successively coupling 55 said manually operable means with said spring motors, said means comprising toothed rims provided upon said spring motors; a toothed pinion slidable parallel to said toothed rims and associated with a nut; a screw spindle associated with 60 said nut; and means for turning said screw spindle to feed said pinion from one spring motor to the following spring motor, operable during the return movement of said manually operable means; means for transmitting the movement of said 65 manually operable means to said spring motors to wind up said spring motors; and a one-way coupling arranged in said movement transmitting means to enable said manually operable means to return into its initial position without moving said 70 spring motors.

8. In a device of the kind described for facilitating correct dialling of automatic telephone apparatus, the sub-combination of: a plurality of 75 spring motors mounted side by side and inde-

- pendently rotatable upon a common shaft, said 5
spring motors having toothed rims; a plurality of
indicator means associated each with a corre-
sponding spring motor; a manually operable
means for winding up said motors; means for
successively coupling said manually operable
means with each of said spring motors, said means
comprising a rotatable pinion and a nut and screw
means for feeding said pinion to engage succes-
sively each of said spring motors, said pinion
being at the commencement of the operation in
engagement with the first spring motor; and
means for moving said pinion into a position
anterior to the first spring motor before the
lease of the said spring motors to turn the dial,
said means comprising a manually operable mem-
ber, and means operable by said calling button
for turning said screw spindle in the opposite
direction.
20. 9. In a device of the kind described for facil-
itating correct dialling of automatic telephone ap-
paratus, the sub-combination of: a plurality of
spring motors mounted side by side and inde-
pendently rotatable upon a common shaft and
provided with toothed rims; a plurality of indi-
cators associated with said spring motors; and
means for successively coupling said spring motors
with the dial of the automatic telephone appa-
ratus, said coupling means comprising: a rotat-
able pinion adapted to co-operate with the toothed
rims of said spring motors, and means for feed-
ing said pinion into successive engagement with
each of said toothed rims, said pinion being nor-
mally placed anterior to the first spring motor.
35. 10. In a device of the kind described for facil-
itating correct dialling of automatic telephone ap-
paratus, the sub-combination of: a plurality of
spring motors provided with toothed rims ar-
ranged side by side and independently rotatable
upon a common shaft; a plurality of indicators
associated with said spring motors; a manually
operable means for successively winding up each
of said spring motors and simultaneously setting
the associated indicator; a separate spring motor
adapted to be wound up upon each operation of
said manually operable means; a longitudinally
slidable pinion adapted to engage in succession
each of said spring motors to couple same with
said manually operable means, said pinion being
50 at the commencement of the operation engaged
with the first spring motor; a second longitudi-
nally movable pinion adapted to engage succes-
sively said spring motors and transmit their driv-
ing movement to the unwinding of the springs,
55 to the dial of the automatic telephone apparatus,
said second pinion being at the commencement
of the operation located anterior to the first
spring motor and not in engagement therewith;
means for feeding said second pinion operated by
60 said separate spring motor; a calling button; a
cancelling button; means operable by said calling
button for moving said first pinion from its ex-
treme position in which it engaged the last
spring motor into a position anterior to the first
65 spring motor; and means operable by said calling
button for moving said second pinion into engage-
ment with said first spring motor; and means
operable by said cancelling button for releasing
simultaneously all the spring motors with the
70 exception of the separate spring motor to cause
them to return to their initial position without
affecting the dial.
11. In a device of the kind described for facil-
itating correct dialling of automatic telephone ap-
paratus, the sub-combination of: a plurality of
spring motors provided with toothed rims and
mounted side by side and independently rotatable
upon a common shaft; a plurality of indicators
associated with said spring motors; means for
successively coupling said spring motors with the
dial of the automatic telephone apparatus; said
coupling means comprising: a rotatably and lon-
gitudinally movable driving pinion adapted to
co-operate with the toothed rims of said spring
motors, a separate spring motor for feeding said
pinion into engagement with each of said toothed
rims and for returning said feeding pinion into
its initial position; and a reversing gear inter-
posed between said driving pinion and said spring
motor; and means for automatically reversing
said reversing gear at the end of the forward feed
of the driving pinion.
12. In a device of the kind described for facil-
itating correct dialling of automatic telephone ap-
paratus, the subcombination of: a plurality of 20
spring motors provided with toothed rims and
mounted side by side and independently rotatable
upon a common shaft; a plurality of indicators
associated with said spring motors; means for
successively coupling said spring motors with the 25
dial of the automatic telephone apparatus; said
coupling means comprising: a rotatably and lon-
gitudinally movable driving pinion adapted to co-
operate with the toothed rims of said spring
motors, a separate spring motor for feeding said 30
pinion into engagement with each of said toothed
rims and for returning said feeding pinion into
its initial position; and a reversing gear inter-
posed between said driving pinion and said spring
motor; and means for automatically reversing 35
said reversing gear at the end of the forward feed
of the driving pinion, said means for reversing
said reversing gear comprising: firstly a push rod
operated by the last wound up spring motor; sec-
ondly a stationary stop coming into action at the 40
end of the advance feed of the driving pinion;
thirdly a second stationary stop provided at the
other end of the travel of the driving pinion.
13. In a device of the kind described for facil-
itating correct dialling of automatic telephone ap-
paratus, the sub-combination of: a casing con-
taining the complete apparatus; a disc rotatably
mounted upon the under side of said casing co-
axially with the dial of the automatic telephone
apparatus, said disc serving for driving the dial 50
and engaging by means of a coupling pin the last
hole of the dial, said casing being adapted to be
mounted above the dial of the automatic tele-
phone apparatus.
14. In a device of the kind described for facil-
itating correct dialling of automatic telephone ap-
paratus, the sub-combination of: a dial; a plu-
rality of spring motors mounted upon a common
shaft; a plurality of indicators bearing call par-
ticulars, each of the indicators being associated
with a corresponding spring motor; one common
manually operable means for operating in suc-
cession all said spring motors and associated in-
dicators, one indicator and one corresponding mo-
tor at the same time; a driving connection be-
tween said spring motor and said dial; said in-
dicators comprising endless bands bearing call
particulars; and a driving connection between
said indicators and said motors comprising flexi-
ble tension members passed around the spring 70
motors, the ends of said member being crossed
and fixed to said endless indicator bands.
15. A device for facilitating correct dialling of
automatic telephone apparatus comprising in
combination: a mechanical driving motor; man- 75

- ually operable means for first selecting at will and visibly indicating as a whole and in proper alignment all the particulars of a proposed call and simultaneously winding up said mechanical driving motor; and means for subsequently automatically driving the dial of an automatic telephone apparatus in accordance with the selected set of particulars, controlled by said first-mentioned means and driven by said motor.
10. 16. A device for facilitating correct dialling of an automatic telephone apparatus comprising in combination: a mechanical driving motor; manually operable means for first selecting at will and visibly indicating as a whole and in proper alignment all the particulars of a proposed call and simultaneously winding up said motor; means for subsequently automatically driving the dial of an automatic telephone apparatus in accordance with the selected set of particulars, controlled by said first-mentioned means and driven by said motor; and means for automatically returning said first-mentioned means to their initial position.
15. 17. A device for facilitating correct dialling of an automatic telephone apparatus comprising in combination: a mechanical driving motor; manually operable means for first selecting at will and visibly indicating as a whole and in proper align-

ment all the particulars of a proposed call and simultaneously winding up said motor; means for subsequently automatically driving the dial of an automatic telephone apparatus in accordance with the selected set of particulars, controlled by 5 the first-mentioned means and driven by said motor; and means for automatically returning the means for selecting and visibly indicating the particulars of the call and the means for driving the dials to their initial positions after the completion of the dialling operation.

18. A device for facilitating correct dialling of an automatic telephone apparatus, comprising in combination: a mechanical driving motor; manually operable means for first selecting at will 15 and visibly indicating as a whole and in proper alignment all the particulars of a proposed call and simultaneously winding up said motor; means for subsequently automatically driving the dial of an automatic telephone apparatus in accordance with the selected set of particulars, controlled by 20 said first-mentioned means and driven by said motor; and separate independently operable means for returning to their initial positions the means for selecting and visibly indicating particulars of a call for the purpose of cancelling an incorrectly set set of particulars.

CARL JOSEF HILGERS.
